ERNEST R. BEASLEY

INVENTOR.

BY

Richard B. Owen

ATTORNEY.

UNITED STATES PATENT OFFICE.

ERNEST R. BEASLEY, OF ABERDEEN, WASHINGTON.

COLLAR.

Application filed July 5, 1921. Serial No. 482,378.

This invention relates to new and useful improvements in wearing apparel and more particularly to collars.

An important object of the invention is to provide a collar which obviates the use of a collar button at the medial or back portion thereof which is ordinarily used for preventing the collar from rising upon the wearer's neck. This is accomplished by providing the collar with a tongue which is adapted to engage the collar band of a shirt, the tongue being formed from the collar in a manner that there will be no possibility of its engaging with the neck tie to prevent it from sliding easily around the collar for adjustments.

Another important object of the invention is to provide means for preventing the tongue from tearing away from the collar.

Other objects and advantages of the invention will become apparent during the course of the following description.

In the accompanying drawings forming a part of the application and wherein like numerals are employed to designate like parts throughout the several views,

Figure 1 is a transverse section of a well known type of collar having its back portion provided with my invention.

Figure 2 is a transverse vertical section through a modification of the invention.

Figure 3 is a transverse horizontal section through the invention taken on the line 3-3 of Fig. 2, and

Figure 4 is a transverse vertical section showing the reinforcing means for the collar.

Referring now more particularly to the drawing wherein for the purpose of illustration is shown the preferred embodiment of the invention, the numeral 5 designates the back portion of a neck band of an ordinary shirt and which is provided with a downwardly opening pocket 6 formed by doubling the neck band. The outer portion of the doubled neck band at the medial portion thereof is ordinarily provided with a button hole for the reception of a collar button usually employed for holding the back of the collar in engagement with the neck band. However, when my improved collar is used in connection with the pocket 6, no button hole nor button is necessary.

To take the place of the ordinary button and button hole, I provide the medial portion of the inner fold 7 of a collar 8 with

a tongue 9. This tongue is provided by slitting or cutting the inner fold 7 as shown at 10 in Figure 1 in a semi-circular line. The ends of the incision are arranged adjacent the lower edge of the inner fold 7 of the collar so that the relative lower portion of the tongue will be secured to the fold and its relative upper end will be free. Consequently, it may be said that the tongue 9 extends upwardly toward the top folded edge of the collar.

In order to prevent the edges of the incision from raveling and the tongue from being torn from the collar, the edges of the incision are worked in button hole fashion as indicated in Figure 1.

As clearly shown in Figure 4 and Figure 1, the rear portion of the inner fold 7 around the tongue, is provided with an extra ply of cloth 11 so that this portion of the collar may receive more starch for reinforcing the same and rendering the tongue stiffer. This ply of cloth may be easily inserted in the collar so that it will not show or rub the neck of the wearer and is of course also slit in when the tongue is being provided in the collar. In order to make doubly sure that the tongue will not be torn from the collar, the lower free edge of the inner fold 7 at the medial portion thereof, is provided with a reinforcing strip 12 of any suitable material, this strip being inserted between the plies of the collar as best seen in Figure 4. It will also be noted that the strip 12 is arranged between the free edge of the inner fold and the incision, and that the ends of incision extend into the strip so that the tongue can not be torn from the collar.

In use, a cravat is associated with the collar in the well known manner after which the collar is placed around the neck so that the tongue 9 is disposed adjacent the pocket 6 in the neck band. Then, with one hand the operator forces the tongue 9 inwardly so that it may be slipped up under the pocket 6. In the present instance, the free edge of the tongue is shown as being semi-circular in configuration so that no corners will be presented which would prevent the tongue from slipping easily into place. After the collar has been thus adjusted, the collar button in the free ends of the neck band is passed through the button holes in the free ends of the collar in the well known manner after which the cravat is tied

in place. When this has been accomplished, it will be seen that it will be impossible for the back of the collar to slip upwardly on the neck since the free end of the tongue 5 will abut the folded portion of the neck band. Furthermore, since the rear portion of the collar and the tongue are stiffened, the collar will not become bent or rumpled from constant use. A good feature of the 10 collar is that the cravat may be easily adjusted since there is no collar button in the back of the collar on which the cravat can catch.

The foregoing description and accompanying drawings have reference to what might be considered to be the approved or preferred form of my invention. I desire it to be understood that I may make such changes in the construction, combination 20 and arrangement of parts, material, dimension, etc. as may prove expedient and fall within the scope of the appended claim.

Having thus described my invention what I claim as new and desire to secure by Letters Patent is:

A collar consisting of a piece of material folded upon itself to form inner and outer folds, said inner fold having an extra ply of material on a portion of its inner face, said inner fold and extra ply being provided with an incision therein to provide an upwardly extending tongue, the opposite ends of the incision being arranged adjacent the lower edge of the inner fold, a relatively narrow reinforcing strip arranged along the lower edge of the inner fold between the same and the extra ply of material to form a ridge between the outer fold and said extra ply and to retain the part of the extra ply above the strip spaced from the outer fold of the collar when the same is in use, said reinforcing strip having cut-out portions to align and communicate with the ends of the incision, and stitching around the incision and the cut-out portions and 45 extending through the reinforcing strip, the inner fold and the extra ply of material.

In testimony whereof I affix my signature.

ERNEST R. BEASLEY.
